UNITED STATES PATENT OFFICE.

ERNEST E. YAXLEY, OF CHICAGO, ILLINOIS, ASSIGNOR TO AMERICAN ELECTRIC TELEPHONE COMPANY, OF CHICAGO, ILLINOIS, A CORPORATION OF NEW JERSEY.

COMBINED LIGHTNING-ARRESTER AND BINDING-POSTS.

SPECIFICATION forming part of Letters Patent No. 701,122, dated May 27, 1902.

Application filed March 13, 1901. Serial No. 50,968. (No model.)

To all whom it may concern:

Be it known that I, ERNEST E. YAXLEY, a citizen of the United States of America, and a resident of Chicago, Cook county, Illinois, have invented a certain new and useful Improvement in a Combined Lightning-Arrester and Binding-Posts, of which the following is a specification.

My invention relates to a form of lightning-arrester adapted more particularly for use in connection with and for the purpose of protecting the various devices and instruments involved in a subscriber's telephone set.

Generally stated, the object of my invention is to provide a simple, efficient, and comparatively inexpensive lightning-arrester of the foregoing character.

A special object is to provide an arrester which may be also employed for making the usual connection between the telephone set and line-wires, so as to obviate the necessity of employing two separate and distinct devices.

Another object is to provide a construction and relative arrangement which will afford ready and convenient access to the different parts, so as to facilitate cleaning and repair and so as to also facilitate the making of any necessary adjustments—as, for example, in grounding either side of the line or in short-circuiting the subscriber's set during a severe electrical storm.

The nature and advantages of my invention will, however, hereinafter more fully appear.

Reference may now be had to the accompanying drawings, in which—

Figure 1 is a plan view of my improved lightning-arrester shown mounted upon a base. Fig. 2 is a side view of the same. Fig. 3 is a diagrammatic view illustrating the connections of the line and lightning-arrester to its earth connection. Fig. 4 is a view showing the lightning-arrester in position upon the apparatus of a subscriber's telephone set.

I have shown the lightning-arrester A as it is designed to be attached to the front of a subscriber's telephone set, this apparatus consisting, as shown, of a base C and binding-posts mounted thereon, the binding-posts C² C³ receiving the line-wire D and the binding-post E being connected to the earth or ground

at E². Each binding-post has a collar J, providing a central opening through it, and a carbon-pencil section or elongated circular block 55 J², held to the binding-post by extending through said collar and by the set-screw J. These carbon-pencil sections J² when mounted and held rigidly upon the binding-posts in the manner described are positioned end to 60 end, the inner end surface of the line binding-post carbon sections being in close proximity to the ends of the section of carbon held in the ground binding-post. Thus the discharging-surfaces of the carbon sections 65 are in close proximity to one another, separated only by a small air-space between them. In the normal operation of a telephone apparatus the currents on the line-wire pass from the incoming binding-post C² through the instrument to the outgoing binding-post C³, as the air-spaces between the carbon sections present a relatively higher resistance than the resistance of the instrument itself. When, however, a disruptive lightning discharge of 75 an extremely high potential encroaches upon the line, it tends to seek the nearest ground, and therefore passes from the line and binding-post into one of the carbon sections and disruptively discharges from the line carbon 80 section to the carbon section held in the ground binding-post and from thence to the ground or earth. When metal is employed, the tendency of the repeated disruptive discharges is to form papillæ between the presented metal ends of the arrester, and thus establish a permanent path between the sections and short circuit the telephone instrument. In my improved form of arrester by employing carbon sections, which is relatively 85 a highly-refractory material, this tendency to form a short-circuiting path is diminished, and should the short-circuiting path form between the ends of the carbon sections it is evident that the air-spaces may be restored by conveniently cleaning the presented end surfaces of the carbon sections. This may be done by 90 means of paper or any other substance inserted between the carbon ends. Further, it often becomes necessary during the continuance of 95 a severe electrical storm to establish a permanent short-circuiting path to earth between the two binding-posts of the instrument, thus short-circuiting the instrument and taking it 100

out entirely of the telephone-circuit. This may readily be accomplished with my apparatus by loosening the set-screws j and pressing the two outer carbon sections C^2 and C^3 5 intimately into contact with the intermediate ground carbon section and then setting up the set-screws, rigidly holding the outer sections in such intimate contact. It is often desirable to connect one side of the circuit to 10 ground through the lightning-arrester apparatus, and this may be conveniently accomplished in my apparatus by loosening the set-screw j of the binding-post connected with the line to be grounded and then bringing 15 the carbon section of that binding-post firmly into contact with the intermediate carbon section held by the ground binding-post and then set up the set-screw to maintain such intimate contact. It will be seen that each 20 binding-post is, with the exception of the socket for the carbon, substantially of the usual form and provided at its top or outer end with a set-screw l for holding a wire in the relatively small transverse opening 2. 25 The base of each binding-post is preferably adapted to be secured to the common base C in any suitable or well-known manner. In this way each binding-post is provided at a point between its ends with a relatively large 30 socket or transverse opening for a carbon and also with the set-screw j' for holding the carbon in place. In this way the fastening devices for securing the wires in place are located immediately above or outside of the 35 carbon-sockets. With this arrangement and construction the wires are easily and conveniently secured in place to the tops of the binding-posts, and, as stated, the carbons are in position to be easily adjusted and cleaned. 40 It is evident that in my apparatus these adjustments for the purpose of short-circuiting the instrument or connecting either line-wire to ground through the lightning-arrester may be accomplished with facility and convenience, and it is also apparent that when it 45 is desired to restore the apparatus to the normal conditions proper adjustments between the sections of carbon may be obtained accurately and conveniently. The lightning- 50 arrester as so constructed also presents a compact and substantial piece of self-contained apparatus.

If arranged close together, as shown, the middle carbon can be removed by sliding it 55 out through one of the outside posts. In this way the three carbons may be readily removed without detaching the posts. Practically the carbons are capable of unlimited adjustment in either direction. With this 60 construction and relative arrangement the carbons are, as stated, easily accessible and readily adjustable to suit the requirements. Furthermore, the device is adapted to serve both as a lightning-arrester and as a binding- 65 post arrangement for making the usual connection between the telephone set and line-wires. In this way the invention obviates

the necessity of employing two separate devices for these different purposes.

Having thus described my invention, what 70 I claim as new therein, and desire to secure by Letters Patent, is—

1. A lightning-arrester comprising three combined carbon-holders and binding-posts, each post having a transverse opening, three 75 carbons held end to end in said openings and arranged in line, the head of each post being provided with a screw-threaded member for securing a wire in place.

2. A lightning-arrester comprising a plurality of combined carbon-holders and binding-posts, each post being formed with a base and a head and also with an enlarged middle or intermediate portion having a transverse opening, adjustable carbons held end to end 85 in said openings and arranged in line, the head of each post being provided with a screw-threaded member for securing a wire in place.

3. The combination of three metal posts having their bases secured to a support and 90 arranged close together in a row, a cylindric piece of carbon extending transversely through the middle portion of each post, the three carbons thus arranged end to end in a line being capable of unlimited endwise adjustment in either direction, and screw-threaded members mounted upon the heads 95 of said posts and adapted for securing wires in place.

4. A lightning-arrester comprising three 100 metal posts having their bases secured to a support and arranged close together in a row, each post being provided with a transverse opening, three carbons held end to end in 105 said openings and arranged in line, said carbons being capable of unlimited endwise adjustment in either direction, screws holding the carbons in place, a screw-threaded member for connecting the middle post with a grounded conductor, and screw-threaded 110 members for connecting the outside posts with the circuit-conductors.

5. A lightning-arrester for use in connection with a subscriber's telephone set, consisting of three binding-posts having their 115 bases secured to a suitable support, each binding-post being provided with a transversely-extending socket or opening, the said binding-posts being arranged in a row with their said openings or sockets in line, cylindric 120 pieces of carbon mounted in said sockets or openings and held end to end, set-screws for holding the carbons in place, the free end of each binding-post being provided with a relatively small transverse opening adapted to 125 receive a wire, and also with a longitudinally-extending set-screw for holding a wire in said relatively small opening.

Signed by me at Chicago, Cook county, Illinois, this 11th day of March, 1901.

ERNEST E. YAXLEY.
